SLEEVE HOLDER

John B. Masse, Lawrence, Mass.

Application September 13, 1934, Serial No. 743,907

2 Claims. (Cl. 24—15)

This invention relates to sleeve holders, and similar devices, and has for one of its objects the production of a simple and efficient sleeve holder which may be readily and conveniently attached to a sleeve for the purpose of shortening the sleeve and at the same time preventing the sleeve from accidentally tearing at its point of adjustment.

A further object of this invention is the production of a simple and efficient sleeve holder which will grip the sleeve at its folded portion at two spaced points, at which points a specially designed clip is provided for gripping the fabric of the sleeve to hold the sleeve in its proper or desired adjusted position.

A still further object of this invention is the production of a simple and efficient sleeve adjusting strap having knobs arranged at spaced intervals over which knobs the fabric of the sleeve is adapted to be placed whereby a specially designed clip may be clamped over the fabric and around the knobs to adjustably hold the sleeve in a shortened or adjusted position.

Another object of this invention is the production of a simple and efficient sleeve adjusting device which will grip the sleeve in a proper manner to hold the same in a shortened position without injury or contact with the arm.

In the drawing:—

Figure 1 is a front elevation of the figure of a person showing one sleeve adjusting device in fully adjusted position and the other sleeve adjusting device in a partially adjusted position;

Figure 2 is an enlarged front elevation of one end of the adjusting band showing the manner in which the clip is secured around one of the knobs of the adjusting band;

Figure 3 is a section taken on line 3—3 of Figure 2;

Figure 4 is a horizontal section taken on line 4—4 of Figure 2;

Figure 5 is a front elevation of the adjusting band;

Figure 6 is an edge elevation of the adjusting band;

Figure 7 is a perspective view of the adjusting band;

Figure 8 is a detail perspective of one of the clips used in connection with the adjusting band.

By referring to the drawing, it will be seen that one of the elements of the present invention is an adjusting band B which consists of an elongated preferably flexible shank 10 having enlarged circular end portions 11 which support studs 12, the studs 12 at each end carrying an enlarged circular head 13. The outer face of the head 13 is

enlarged circular end portion 11 in each instance, to permit the fabric of the sleeve 14 to be folded around over the head 13, as shown clearly in detail in Figures 3 and 4. Due to the fact that the shank 10 is preferably of a material which may easily flex, it will be seen that the elongated shank may easily conform to the contour of the arm and hold the sleeve snugly around the arm when the band B is placed in position. These heads 13 are arranged, one at each end of the shank 10, and are preferably spaced a material distance apart to permit the gripping of the sleeve at spaced intervals thereby preventing the sleeve from sagging as would be the case if the sleeve were only gripped at one point. The heads 13 preferably are provided with beveled outer faces 15 to allow the fabric to easily and conveniently fit over the heads thereby reducing the danger of tearing the fabric of the sleeve.

In conjunction with each head 13, I employ a specially designed clip C preferably formed of spring wire. This clip C comprises a spring arm 16 having a finger gripping knob 17 at its outer end. The spring arm 16 terminates in a right-angularly extending bridge portion 18, which right-angularly extending bridge portion is connected to a diverging spring arm 19, the diverging spring arm 19 having an inwardly bent hook 20 formed from the wire of the arm 19, this hook 20 in turn terminating in an upwardly extending finger 21 extending in alignment with the spring arm 19 and carrying a finger engaging knob 22 preferably in transverse alignment with the knob 17. As the knobs 22 and 17 are drawn together by the finger of the operator the hook 20 is adapted to fit around the spring arm 16, such as is shown in Figure 2 when the clip C is placed over one of the heads 13 so as to fit behind the head and around the stud 12. The arms 16 and 19 converge toward their lower ends or toward the bridge portion 18 and are preferably of spring wire material so as to normally cause the knobs 17 and 22 to be urged apart or in spreading relation, but by pressing the knobs 17 and 22 together the hook 20 may be caused to engage the arm 16 to be held in a closed or locked position. By forcing the knobs 17 and 22 together again, the clip may be manipulated so as to move the same to an open position for the purpose of release.

The operation of the device is as follows:—

One head 13 is placed under the fold of the sleeve 14, when the sleeve has been adjusted to its proper length, and the clip C is fastened over the fabric, which fabric is then drawn closely over the head 13, the clip C snugly fitting around

spaced from the outer face of the shank 10 and the shank 12 of the head 13, and holding the head in engagement with the fabric. The band B is then swung to bring the opposite head 13 in substantial transverse alignment with the first mentioned head and the fabric is folded over the second head at which time a second clip C is secured firmly over a second head 13 as previously described in detail.

- 10 From the foregoing description it will be seen that a very simple and efficient sleeve holder has been provided wherein the fabric of the sleeve may be firmly gripped at spaced intervals and then folded over the heads 13 of the band B whereupon the spring clips C may be in turn quickly snapped over the heads 13 thereby holding the fabric 14 of the sleeve in a properly adjusted position. Due to the fact that the heads 13 are relatively large, the wire clips C will not 15 have a tendency to tear the fabric particularly in view of the flexible nature of the clips and the beveled head formed upon the head. Furthermore, the elongated shank 10 which is preferably flexible will permit the sleeve, as well as 20 the band B, to flex or conform substantially to the contour of the arm. The fabric may be loosely arranged between the respective heads so as to permit the flexing of the shank 10 without fear of 25 too much strain laterally upon the fabric.

It should be understood that the present holder, although especially designed for the purpose of adjustably holding a sleeve, may be employed for any similar purpose without departing from the spirit of the invention and it is not desired 5 to limit the present invention to merely a sleeve holder.

Having described the invention, what is claimed as new is:—

1. In combination with a securing band having a shank rigid longitudinally and yieldable transversely, spaced heads carried near the respective ends of the shank, said heads being adapted to engage a piece of fabric, and removable spring clips adapted to fit about the heads 15 for detachably holding a piece of fabric in engagement with the heads.

2. In combination with a band having a relatively thin elongated shank rigid longitudinally and yieldable transversely, spaced heads carried 20 by the shank at its respective ends, each head having a reduced neck for securing the head to the shank, the heads being adapted to fit under the fabric of a sleeve to permit the holding of the sleeve in an adjusted length, and a spring 25 clip removably fitted about the shank of each head for firmly holding the fabric of the sleeve in an adjustable clamped position over the heads.

JOHN B. MASSE.
